AUTOMOBILE RADIO ANTENNA

Arthur T. Mace and Kenneth C. Bureaw, Cleve-
land, Ohio, assignors to The Radiart Corpora-
tion, Cleveland, Ohio, a corporation of Ohio

Application April 1, 1939, Serial No. 265,494

6 Claims. (Cl. 250—33)

This invention relates, as indicated, to vehicle radio antennae but has reference more particularly to radio antennae for use on automobiles or like vehicles, in conjunction with radio receiving sets.

A common type of radio antenna now in use comprises an adjustable antenna rod carried by two vertically spaced insulators or supports which project laterally from the side of the cowl of the automobile body. The attachment of the insulators or supports to the cowl in such case involves the drilling or punching of holes in the exposed portion of the cowl for the reception of the bolts or other connections to the insulators. The drilling of such holes is objectionable, principally for the reason that moisture may seep into the space between the insulators and the cowl and find its way to the holes, resulting in rusting of the cowl at these points, as well as rusting of the insulator supporting elements.

A primary object of the present invention is to provide a radio antenna of the type described which is supported on the automobile body in such a manner as to obviate the drilling of holes in the exposed portion of the cowl.

Another object of the invention is to provide a radio antenna of the type described, which is inexpensive to manufacture, and which can be quickly and easily attached to the automobile body.

Other objects and features of the invention will appear hereinafter.

In the accompanying drawing:

Fig. 1 is a side elevation of a portion of an automobile, illustrating the mounting of the antenna on the automobile body;

Fig. 2 is a fragmentary horizontal cross-sectional view, taken on the line 2—2 of Fig. 1, and

Fig. 3 is a fragmentary cross-sectional view, taken on the line 3—3 of Fig. 2.

Referring more particularly to the drawing, there is illustrated an automobile having a cowl 1 and a hood 2, the cowl having an inwardly offset flange 3, which is normally covered by the hood when the latter is in closed position as shown. The space between the hood and the offset flange 3 of the cowl is usually filled, at spaced points by means of pieces of felt or other soft, sound-deadening material (not shown).

Secured to the offset flange 3, as by means of stove bolts 4 and nuts 5 are metal plates 6 and 7, which are substantially coextensive in width with the flanges 3 and have outwardly offset portions 8 and 9 respectively, which are parallel with the plates 6 and 7. The portions 8 and 9 are re-

spectively provided with horizontally extending flanges 10 and 11, which are in continuity with each other, and which are apertured to receive the reduced base portions 12 of conical-shaped insulators 13. The base portions 12 of the insulators are also in continuity with each other so as to provide in effect a single continuous body of insulating material.

The insulators are provided with aligned axial bores 14, through which extends a threaded bolt 15, the upper end of which projects above the upper end of the upper insulator 13, and have secured thereto, the tubular base portion 16 of the antenna rod 17. The lead-in conductor 18 from the antenna rod to the receiving set is secured between the head 19 of the bolt 15 and a lock washer 20. The antenna rod and its connections are thus completely insulated from the plates 6 and 7.

It should be noted that the plates 6 and 7 are movable angularly with respect to each other about the axis of the antenna rod. This is to compensate for irregularities in the flange 3 of the cowl.

It is to be further noted that the mounting of the antenna rod in the manner described permits the lead-in conductor 18 to be run to the receiving set through the joint between the cowl and hood of the automobile, as indicated in Fig. 1.

It is thus seen that a radio antenna has been provided which is supported on the automobile body without the necessity of drilling or punching holes in the exposed portion of the cowl, which consists of a minimum number of inexpensively manufactured parts, and which can be quickly and easily attached to the automobile body.

Other modes of applying the principle of my invention may be employed instead of the one explained, change being made as regards the structure herein disclosed, provided the means stated by any of the following claims or the equivalent of such stated means be employed.

We therefore particularly point out and distinctly claim as our invention:

1. In an automobile, a cowl having an inwardly offset flange at its forward edge, a hood having a portion overlapping said flange, a radio antenna, and means for supporting said antenna, said means comprising a bracket having an offset flange secured to said cowl flange, said bracket flange being normally covered by said hood.

2. Radio antenna apparatus for mounting on the outside of a vehicle body having a movable cover portion, in a manner such that the nor-

mally visible portions of the vehicle body are not defaced, said antenna apparatus including a body portion having a mounting extension extending laterally therefrom, said antenna body portion having a cavity extending in and elongated in a direction substantially at right angles to the extending direction of said mounting extension, an aerial having a portion extending into said cavity, and insulating means in said cavity supporting said aerial in said cavity in a generally vertical direction and insulating said aerial from the antenna body portion, with a portion of said mounting extension adapted to be secured to the vehicle body so that said mounting extension portion is substantially concealed by said movable cover portion of the vehicle and being so thin as not to interfere with a normal position of the movable cover portion, with the antenna body portion being exposed on the outside of the vehicle.

3. The combination of a radio antenna, and means for supporting said antenna, said means comprising a pair of brackets, a flat face forming part of each bracket to enable said brackets to be positioned face to face adjacent each other, an insulating block interconnecting said brackets and interposed between said antenna and said brackets to insulate the antenna from the brackets and means to hold said brackets, said insulator and said antenna in operative relation to each other.

4. The combination of a radio antenna, and means for supporting said antenna in generally vertical direction, said means comprising a pair of brackets, a flat face forming part of each bracket to enable said brackets to be positioned face to face adjacent each other, an insulating

block interconnecting said brackets and interposed between said antenna and said brackets to insulate the antenna from the brackets and means to hold said brackets, said insulator and said antenna in operative relation to each other.

5. In an automobile, a cowl, a hood having a portion overlapping a part of said cowl, a radio antenna, and means for supporting said antenna on said covered part of said cowl, said means comprising a pair of brackets, a flat face forming part of each bracket to enable said brackets to be positioned face to face adjacent each other, an insulating block interconnecting said brackets and interposed between said antenna and said brackets to insulate the antenna from the brackets and means to hold said brackets, said insulator and said antenna in operative relation to each other.

6. Radio antenna apparatus for ready mounting on the outside of an automobile in a manner to provide the advantages of an outside mounted antenna and yet without defacing normally visible portions of the automobile body, said antenna apparatus including a metal body portion having an axial bore therein, insulating means providing an insulating lining for said bore, portions of said insulating means extending out of each end of said bore, an aerial supported by said insulating means and extending axially above one of said insulating means portions, an extension of said metal body portion intermediate said insulating means portions and extending to one side thereof and an apertured mounting member connected to said extension.
